[57] CLAIM

The ornamental design for a boat cup holder, as shown and described.

DESCRIPTION

FIG. 1 is a perspective view of a boat cup holder showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of my cup holder and of the mounting sleeve which receives the same;

FIG. 9 is a perspective view of my cup holder after insertion thereof in the mounting sleeve shown in FIG. 8;

FIG. 10 is a perspective view of a second embodiment of the boat cup holder;

FIG. 11 is a left side elevational view thereof;

FIG. 12 is a right side elevational view thereof;

FIG. 13 is a top plan view thereof;

FIG. 14 is a bottom plan view thereof;

FIG. 15 is a front elevational view thereof; and,

FIG. 16 is a rear elevational view thereof.

The portions shown in broken lines in FIGS. 8 and 9 are for information only and form no part of the instant design.
